UNITED STATES PATENT OFFICE.

WILLIAM KELSOW, OF HOBOKEN, NEW JERSEY.

DESIGN FOR A CRUET-STAND.

47,261.

Specification for Design.

Patented Apr. 27, 1915.

Application filed February 16, 1915. Serial No. 8,636. Term of patent 7 years.

To all whom it may concern:

Be it known that I, WILLIAM KELSOW, a citizen of the United States, residing at Hoboken, in the county of Hudson and State of New Jersey, have invented a new, original, and ornamental Design for Cruet-Stands, of which the following is a specification, reference being had to the accompanying drawing, forming part thereof.

The figure is a perspective view of a cruet stand showing my new design.

I claim:

The ornamental design for a cruet stand, substantially as shown.

WILLIAM KELSOW.

Witnesses:

FRANK V. BRIESEN,
MADELINE L. HIRSCH.
